UNITED STATES PATENT OFFICE.

JOHN H. McCUNE, OF KAW, OKLAHOMA.

WASHBOILER.

1,099,072.

Specification of Letters Patent.

Patented June 2, 1914.

Application filed May 28, 1913. Serial No. 770,415.

To all whom it may concern:

Be it known that I, JOHN H. McCUNE, a citizen of the United States, residing at Kaw city, in the county of Kay and State 5 of Oklahoma, have invented new and useful Improvements in Washboilers, of which the following is a specification.

This invention is an improved wash boiler, the object of the invention being to 10 provide an improved wash boiler which embodies a bottom, a perforated semi-tubular false bottom having its edges secured to the bottom, a water heating coil arranged below the bottom and connected at its ends to the 15 bottom at points under the false bottom, and further provided with upwardly projecting tubular arms connected to the perforated false bottom and having openings in their sides to discharge jets of hot water laterally into the vessel, the perforated semi- 20 tubular false bottom acting to discharge jets of hot water upwardly in the boiler, the invention consisting in the construction, combination and arrangement of devices 25 hereinafter described and claimed.

In the accompanying drawings: Figure 1 is a plan of a wash boiler constructed in accordance with my invention with one of the vertical tubular arms shown in section. 30 Fig. 2 is an inverted plan of the same, showing the arrangement of the water heating coil. Fig. 3 is a vertical sectional view on the plane indicated by the line A—A of Fig. 1. Fig. 4 is a similar view on the plane 35 indicated by the line B—B of Fig. 1.

My improved washer or wash boiler is here shown as rectangular in form and comprising a bottom 1 and side walls 2. Two of the side walls are provided at points intermediate 40 their ends with handles 3. The boiler is preferably made of sheet metal. Under the boiler is a water superheating coil 4 which is preferably of the form here shown and is provided at its ends with upwardly extending elbows 5 having nipples 6 attached thereto which extend through and project above openings in the bottom of the boiler near diagonally opposite corners thereof, locking nuts 7 and washers 8 being 45 also provided to securely fasten the nipples and, hence, the ends of the coil to the bottom of the boiler. A false bottom 9 is arranged on the bottom of the boiler on the inner side thereof and is here shown as comprising a pair of U-shaped substantially semi-tubular connected members 10 which

are perforated as at 11 and the edges of which are soldered or otherwise secured to the bottom of the boiler. The ends of these false bottom members 10 are arranged over 60 the ends of the coil where the latter are connected to and extend through the bottom of the boiler so that the coil communicates with the boiler at points under the false bottom. Each of the U-shaped perforated 65 semi-tubular members has a long arm and a shorter arm. The shorter arms of said members are arranged opposite each other and near the center of the vessel and are connected together. Tubular arms 12 project upwardly from the members of the false 70 bottom, have their upper ends closed and are provided with perforations 13 in their sides, these tubular arms being arranged at different points in the boiler, near its corners 75 and at its center.

When the boiler is in use, on a stove or other heater, water is heated in the coil as well as in the boiler and the heated water in the coil by expansion forces its way up 80 into the boiler under the false bottom members, upwardly from the latter through the openings therein in jets through the clothes in the boiler and also in lateral jets through the clothes in the boiler from the perforations in the vertical tubular arms. Hence, the water in the boiler is caused to keep in circulation and such movement of the water in addition to the action of the jets produced by the false bottom and heating coil 85 causes the clothes to be rapidly and thoroughly cleansed. By the arrangement and construction of the pair of U-shaped perforated semi-tubular members, perforations are provided at all points on the bottom of 90 the boiler so that at points where the water is hottest and there can be a flow from the coil to the interior of the boiler and the points where the temperature is not so high and can be returned from the boiler back 95 to the coil.

While I have herein shown and described a preferred form of the invention, I would have it understood that changes may be made in the form, proportion and construction of the several parts without departing from the spirit of the invention and within the scope of the appended claim.

I claim:—

The herein described wash boiler comprising a vessel having a bottom, a false bottom in the vessel and comprising a pair

of U-shaped perforated semi-tubular members each having a long arm and a shorter arm, the shorter arms of said members being arranged opposite each other, a connecting member between said shorter arms, said members having their edges secured to the bottom, a water heating coil arranged below the bottom and connected at its ends to the bottom at points under the terminal portions of the longer arms of the false

bottom members and tubular perforated arms extending upwardly from the members of the false bottom and having their upper ends closed.

In testimony whereof I affix my signature 15
in presence of two witnesses.

JOHN H. McCUNE.
